(57) **CLAIM**

The ornamental design for an optical fiber cable, as shown and described.

DESCRIPTION

FIG. 1 is an enlarged perspective view of a section of an optical fiber cable showing our new design;

FIG. 2 is front elevation view thereof, the back elevation view being identical to the front elevation view;

FIG. 3 is a left side elevation view thereof, the right side elevation view being identical to the left side elevation view;

FIG. 4 is a perspective view thereof, in use condition;

FIG. 5 is another perspective view thereof, in use condition;

FIG. 6 is a cross-sectional view thereof, taken along lines "6-6" of FIG. 5;

FIG. 7 is another cross-sectional view thereof, taken along line "7-7" of FIG. 5; in an exploded condition; and,

FIG. 8 is another cross-sectional view thereof, taken along line "8-8" of FIG. 5; in another exploded condition.

The even-broken line shown in the drawing represents unclaimed environment and forms no part of the claimed design, the dash-dot line represents the boundaries of the claimed design.
